LANDING NET

Filed April 7, 1951

UNITED STATES PATENT OFFICE

2,630,646

LANDING NET

Frank Jensen, Clifford W. Jensen, and
Dale Jensen, Trenton, Utah

Application April 7, 1951, Serial No. 219,794

1 Claim. (Cl. 43—12)

1

This invention relates to a quick acting telescoping landing net which is capable of being expelled instantly into operative position and which is easily retracted into its casing.

It is an object of this invention to provide a casing into which the landing net may be held when not in use, but the net can be instantly expelled from the casing into full open position without any damage being done to the net.

It is another object of this invention to provide a cylindrical casing for retaining a landing net and its support means therein, and propulsion means including a spring actuated piston for instantly expelling the landing net and its frame members from the casing, of cord means having its opposite ends associated with the bottom of the net and the front of the casing with a guide tube for the cord secured to the front end of the piston.

A still further object of this invention relates to a quick acting landing net means in which a casing is provided for housing the net when not in use, of frame members for supporting the net having flexible guide means for aiding in expelling the net from the casing and for protecting the net from damage by the frame members when the net is being drawn into the casing.

Other and further objects will become apparent from the detailed description and the subjoined claims.

The accompanying drawings illustrate the invention.

Figure 1 is a side elevational view of the telescopic landing net and its casing, the net being in expelled position from its casing or in its operative position, parts in section, and parts broken away.

Figure 2 is a top plan of the telescopic landing net in open position, parts in section and parts broken away.

Figure 3 is a sectional view taken on line 3—3 of Figure 2 showing the guides in the front end of the casing for the frames for the net.

Figure 4 is a sectional view taken on line 4—4 of Figure 1 disclosing the pivot or hinge means for front end of the frame members of the landing net.

Figure 5 is a fragmentary view of the piston, showing the tube for the cord for the landing net and the pivot means for the rear end of frame members of the landing net.

2

Referring in detail to the drawings 10 is the telescopic landing net means which comprises a cylindrical metal casing 12 having a cap 14 removably mounted on one end with an apertured projection by which the net means 10 may be suspended from a hook on the fisherman's belt, etc.

The top of the casing 12 is provided with a longitudinal slot 18 which extends from a point 10 slightly ahead of the cap end 14 of the casing to near the opposite end of the casing. A collar 20 provided with a chamber 22 whose diameter gradually becomes greater from the rear end toward the front end of the collar 20 except for 15 a small circumferential portion 21 at its front end which is of the same diameter throughout its length of receiving a round metal closure plate 50.

A piston member 24 is mounted for sliding movement inside the casing 12. A finger element 26 is secured to the piston 24 by securing means 20 extending through slot 18 and provided with a shank portion 28 and an elevated element 30 provided with a flat face 32 projecting beyond the 25 inner end of the shank 28. A relatively large compression spring 34 is carried in the casing 12 between the cap 14 and the rear end of the piston 24 to provide the expulsion means for automatically extending the fishing net 54 of the device when the net is released from the casing 10. A small hollow tube 36 being open at both ends consisting of a front straight portion extending forwardly and downwardly from the front of the piston 24 and a hook formed in its rear portion and its rear end also extending forwardly and downwardly from the front end of piston 24 is secured by solder 37 to the front end of the piston 24 for a purpose to be set forth hereinafter. A pair of spaced brackets 38—38 are also secured to the front end of the piston 24 and pivot pins 40—40 are vertically mounted in the brackets 38—38 with a metal loop 42 encircling each pin 40.

A pair of frame members 44—44 or collapsible spring bows of thin resilient metal have their inner ends respectively secured to the loops 42—42 carried by pivot pins 40—40 with their opposite ends secured to metal loops 46—46 encircling pivot pins 48—48 vertically mounted in brackets on the round metal plate 50. A plurality of spaced apart apertures are appropriately

formed in the center of each of the collapsible spring bows or frames 44 extending from end to end thereof. A pair of threads 52 are threaded through the plurality of spaced apart apertures in the frames 44—44 securing the upper open end of a landing net 54 to the inside of the frames 44—44. A separate elastic or flexible guide member 56 of rubber or the like extends above and below the upper and lower edges respectively of each of the frames 44—44 and is secured by the threads 52 at their front portions to the inside of the frames 44—44 adjacent their inner ends. The inner portion of each of the elastic guides 56 is secured to the frames 44—44 as at 58, and their inner ends are secured to the front of the piston 24 adjacent the tube 36. The elastic guides 56 prevent the metal frames 44—44 from cutting the net 54 when the net is retracted into the casing 12. The elastic elements 56—56 also aids to wipe or push the net 54 and control cord 60 clear of the casing 12 when the net is expelled from the casing. A cord 60 is secured at one end to the bottom of the net 54 with the opposite end threaded through the tube 36 and secured to the collar 20 at 62. The cord 60 is of sufficient length to extend from the tube 36 to the bottom of the net 54 when the piston 24 is positioned at the front end of the casing 12 and the net 54 is in full open position as shown in Figure 1 of the drawing.

A housing 64 is carried on the outside of the casing 12 near its rear end and latch 66 is pivoted to the housing with a small coil spring 68 normally urging the catch 67 of the latch 66 through an aperture in the casing 12.

When the fishing net 54 is not being used to receive a fish from a fish hook or the like, the left thumb of a user engaging the flat surface 32 of the finger element 26 pulls the piston 24 rearwardly in the casing 12 against the pressure of the compression spring 34 until the catch 67 on latch 66 engages the front end of the piston 24 for holding the net 54 and frames 44—44 in a retracted condition in the casing 12. The net 54 will remain in the casing as long as the latch 66 is allowed to retain the piston 24 in its retracted position therein.

A guide groove 70 is formed on opposite sides of the collar 20 on the inside thereof to guide and hold the side frames 44—44 in proper alignment in the casing 12 when the net is being withdrawn into the casing. A smaller groove 72 in each of the larger grooves 70 receives the edges of the threads 52 on the outside of the frames 44—44 either when the net is retracted into the casing or when the net 54 is expelled from the casing to prevent cutting or undue wearing on the threads 52.

The enlarged portion of chamber 22 at the outer end of the collar 20 acts as a shuttle at its lower side by engaging the net 54 as it is being withdrawn into the casing 12 and pushes or wipes the net 54 toward the center of the chamber 22 between the flexible metal guide frames 44—44 thus preventing the guide frames 44—44 damaging the net 54. When the finger element 26 is pulled rearwardly of casing 12 retracting the net 54 into the casing, the control cord 60 is pulled into casing 12 and the end of cord 60 attached to the bottom of the net 54 pulls the bottom of the net up towards the mouth of the collar 20 and the lower end of the net 54 is gradually fed into the casing 12 along with the upper portion of the net insuring that the net will not bunch at the front of the collar 20 and then the plate 75

50 can completely close the front end of the casing 12. The draw or control cord tube 36 acts as a guide for the cord 60 and tube 36 also aids in holding apart the frames 44—44 from each other when collapsed in the casing 12 so that the control cord 60 will not be bound between the frames 44—44. The net 54 corresponds substantially in length to the length of one of the bow springs 44 and control cord 60 corresponds substantially to the length of the net 54 so that when the landing net is telescoped into the casing 12, the frames 44—44, net 54 and cord 60 are completely retracted into and housed in the casing 12.

15 The cover plate 50 completely covers the opening in the collar 20 when the net 54 is withdrawn into the casing 12.

When a fisherman wishes to use the net device and it is collapsed in the casing 12 he merely 20 actuates the latch 66 releasing it from engagement with the piston 24 and the coil spring 34 automatically and instantly moves the piston 24 forwardly in the casing 12 thus expelling the frames 44—44 with the attached net 54 from 25 the front end of the casing 12. The resilient spring bows or frames 44—44 expand thus moving the net 54 to full open position ready for instant use when needed by a fisherman. An intermediate portion of the finger element 26 engages 30 a stop member 15 formed on the collar 20 for limiting the forward movement of the piston 24 in the casing 12.

The front cover plate 50 acts as a hinge plate 35 for the resilient frames 44—44. A hook 80 is secured to the casing 12 and it is used for slipping the device onto the belt of a fisherman.

It is to be understood that changes in the size, shape and dimensions of the device may be 40 resorted to but all such changes are deemed to fall within the scope of the appended claim.

What we claim as new is:

In a landing net, a hollow casing having a removable closure means on one end, the casing 45 being provided with a longitudinal slot, a piston means mounted for sliding movement in said casing, a handle secured to the piston and having securing means to the piston extending through the slot in the casing, a compression spring 50 carried in the casing between the piston and the closure means for the casing to project the piston forwardly in the casing, a net frame consisting of a pair of oppositely spaced spring bows 55 slidably engageable within the hollow casing and having at one of their ends vertically positioned pins secured to the front end of the piston, a closure plate for the front end of the casing provided with a pair of vertically positioned pins for pivotally mounting the opposite ends of the pair of spring bows whereby the pair of spring bows are mounted to extend vertically with respect to the closure plate and the piston, a net corresponding substantially in length to the length of one of the spring bows and secured 60 to the pair of opposed spring bows, a hollow tube mounted on the front of the piston between the pair of spring bows, and a control cord corresponding substantially to the length of the net and having one end secured to the bottom of the net with the cord threaded through the tube and the opposite end of the cord fastened to the casing at the front end thereof for aiding in retracting the net within the casing, said cord being of sufficient length to extend from the control tube to the bottom of the net when the tube

is positioned in the front end of the casing and the net frame and net are in their full open positions, and whereby upon the net frame being retracted into the casing the control cord feeds the net into the hollow casing.
